Lee Burt. Inventor:

UNITED STATES PATENT OFFICE.

LEE BURT, OF DETROIT, MICHIGAN.

APPARATUS FOR CHARGING BLAST-FURNACES.

SPECIFICATION forming part of Letters Patent No. 239,223, dated March 22, 1881.

Application filed December 30, 1880. (No model.)

To all whom it may concern:

Be it known that I, LEE BURT, of Detroit, in the county of Wayne and State of Michigan, have invented a new and useful Improvement 5 in Apparatus for Charging Blast-Furnaces, of which the following is a specification.

The drawing represents a vertical sectional view of the charging apparatus constructed according to my invention.

10 My invention relates to apparatus for charging blast-furnaces; and it consists in hanging the bell at the top of a blast-furnace from the bell-beam by rods which pass through the covering-plate of the top of the furnace outside 15 of the aperture in the covering-plate through which the furnace is charged, so as to leave said aperture entirely unobstructed when the furnace is being charged, and in covering said aperture with a hinged or otherwise removable solid lid.

20 In the charging apparatus now used the bell is connected with the bell-beam by a rod running from the end of the bell-beam directly to the apex of the bell, passing through the center of the lid which covers the charging-aperture, and this lid, when raised, slides on the rod which supports the bell. This rod, running through the center of the charging-aperture, renders it impossible to use a charging- 25 buggy which runs directly over the bell and dumps its load evenly all around the bell, and necessitates the use of a charging-buggy which dumps its load from the side of the charging-aperture, and also prevents the use of a solid 30 gas-tight lid for covering the charging-aperture. These defects are obviated by my invention, which is constructed as follows:

35 I I are sections of the upper end of the walls of a blast-furnace, the top of which is covered 40 by an iron covering-plate, A, having a circular aperture over the center of the furnace.

B B are iron brackets supported by covering-plate A.

45 E is an iron hopper, bolted at its upper end to brackets B, and carrying at its lower end a lip-ring, D, against which the bell closes.

F is a bell of the usual form and construction.

50 N is a bell-beam, which may be counterbalanced and operated in any suitable manner, supported on column O.

M is a chain fastened to the end of bell-beam N.

K is a cross-bar, to the center of which is fastened chain M, and to its ends are fastened 55 the vertical iron rods L L.

G is a cross-bar, to the center of which is fastened the upper end of a vertical rod, H, the lower end of rod H being secured to the apex of bell F. The lower ends of rods L L 60 are fastened to the ends of cross-bar G, so that cross-bars K and G, with rods L L, form a frame or sash, and by raising or lowering cross-bar K bell F will be raised or lowered. Rods L L pass through covering-plate A outside of 65 the charging-aperture.

70 It is obvious that cross-bar G and connecting-rod H may be dispensed with and rods L L attached directly to bell F without departing from my invention.

C is a solid lid, which covers the charging-aperture in covering-plate A. It is hinged at J, and is counterbalanced by a weight attached to chain T, passing over pulley P.

75 S is a curved track for the weight to run upon, and is curved as shown in the drawing, so that as lid C rises and offers less resistance to the weight the track will offer an increasing support to the weight and prevent lid C from being thrown open with a violent jerk. 80

R is the mixture of ore and fuel with which the furnace is to be charged.

When it is necessary to charge the furnace lid C is raised, leaving the charging-aperture entirely clear and unobstructed, so that a bell-bottomed charging-buggy can be run directly over the aperture and its load dumped upon the bell, thus securing an even distribution of the charge around bell F. Hinged lid C is then closed, which prevents any escape of gas 90 when bell F is lowered, and the charge is then put into the furnace by lowering bell F.

95 It will be seen that by the use of my invention the charging-buggy can be run directly over the charging-aperture and its load distributed evenly around the bell, and the escape of gas when the bell is lowered almost entirely prevented.

100 What I claim as my invention, and desire to secure by Letters Patent, is—

1. In a blast-furnace, the combination of a covering-plate having a charging-aperture, a

bell-supporting beam arranged below the charging-aperture, a bell-support arranged above the charging-aperture, and connections attached to the bell and extending through the covering-plate outside the charging-aperture and connected with the bell-support, all substantially as described, for the purpose set forth.

2. In a blast-furnace, the combination, with a covering-plate having a charging-aperture, of a charging-bell arranged below said aperture, vertical rods connected with the charging-bell and extending through the covering-plate outside the charging-aperture, and a bell-supporting beam connected with the pro-

jecting ends of the vertical rods, all substantially as and for the purpose described.

3. In a blast-furnace, the combination of the covering-plate A, having an aperture therein directly over the apex of the bell, solid lid C, bell F, bell-beam N, and frame K L G, connected with the bell-beam above and the bell below, substantially as herein shown and described.

LEE BURT.
